CLAIM

The ornamental design for a acupressure instrument for
applying rolling pressure to the human body, substan-
tially as shown and described.

DESCRIPTION

FIG. 1 is an isometric view of a acupressure instrument
for applying rolling pressure to the human body;
FIG. 2 is a side elevational view thereof;
FIG. 3 is an end view, as viewed from above in FIG. 2,
and
FIG. 4 is an end view, as viewed from below in FIG. 2.

FIG. 1.FIG. 2.FIG. 3.FIG. 4.
